LEWIS R. HEIM, OF DANBURY, CONNECTICUT, ASSIGNOR TO THE BALL AND ROLLER BEARING COMPANY, OF DANBURY, CONNECTICUT, A CORPORATION OF CONNECTICUT.

DEVICE FOR FEEDING ROLLS FOR END-GRINDING.

1,264,928.

Specification of Letters Patent.

Patented May 7, 1918.

Application filed July 13, 1917. Serial No. 180,459.

To all whom it may concern:

Be it known that I, LEWIS R. HEIM, a citizen of the United States, residing at Danbury, county of Fairfield, State of Connecticut, have invented an Improvement in Devices for Feeding Rolls for End-Grinding, of which the following is a specification.

This invention relates to grinding mechanism, and has particular reference to means whereby large numbers of small articles such as bolts, pins, bearing rollers, etc., may be accurately ground on one or both ends, or may be circumferentially ground, with a minimum amount of handling. With this invention, the ends of bearing rollers may be simultaneously ground so that the rollers will be of uniform length, or headed articles such as bolts may be ground on both ends to be of uniform length or the head itself may be ground of uniform length, as may be desired. Numerous other uses for such a mechanism are apparent without specific mention, and a preferred form of the invention will be described herein.

The invention comprises a magazine carrier which may be loaded by hand or automatically, and disposed adjacent one or more grinding wheels so as to successively carry projecting portions of the articles to be ground across the grinding surface or surfaces. As shown herein, the mechanism comprises two grinding wheels with the carrier disposed between and mechanically driven so as to simultaneously grind opposite ends of rollers for roller bearings, but the invention contemplates the substitution of a stationary guide for one wheel in a case where it is only desired to grind one end of the article, and in some instances, as in the case of headed articles which are to be ground on the head, the carrier itself performs the functions of a guide.

In the accompanying drawings,

Figure 1 is an end elevation showing the complete assembly,

Fig. 2 is a top plan,

Fig. 3 is an end view seen from the left in Fig. 1,

Fig. 4 is an elevation on an enlarged scale,

Fig. 5 is a section on the line 5-5 of Fig. 4, and

Fig. 6 is a detail view showing the manner of loading the carrier by hand.

1 represents the base provided with a

stock 2 at each end, each stock carrying a shaft 3 and grinding wheel 4. The stocks 2 are independently adjustable so as to vary the distance between the grinding wheels 4. As herein shown, the grinding wheels 4 have the grinding surfaces on the side, but the invention is equally applicable to peripheral grinding wheels. The grinding wheels 4 are adjusted and driven in any desired manner not necessary to be shown herein.

The base 1 is provided with an upright standard 6 to which is bolted a bracket 7. The bracket 7 carries a shaft 8 on which is rotatably mounted a carrier disk 9 having holes or pockets 10 to receive the rollers 11, or bolts, or other articles as the case may be, and also having gear teeth 12 which mesh with the pinion 13 mounted on shaft 14 journaled in the bracket 7 and driven by pulley 15. Mounted on the upper side of the bracket 7 above the shaft 8 and closely adjacent to the grinding wheels 4 are guide plates 16, having outwardly curved edges at the entrance side as shown in Figs. 2 and 4. The guide plates 16 are separated by a spacing piece 18, a distance apart corresponding to the length or thickness of the rough blanks, and the flared or outwardly curved edges of the guide plate provide a rearwardly tapering entrance to the guide afforded by said guide plates and thus serve to position the blanks in the carrier so that the carrier will feed the blanks properly to the grinding wheels. Where side grinding wheels are used, it is desirable to accurately position the blanks so that only their ends or projecting portions will come in contact with the grinding wheels. If peripheral grinding wheels be used, it will be understood that the carrier shaft 8 will be normal or nearly so to the axes of the grinding wheels, instead of parallel thereto, as shown herein.

The operation will be readily understood from the drawings in view of the foregoing description, it being understood that the grinding wheels rotate counter-clockwise, and the carrier rotates clockwise. The operator places the blanks in the magazine carrier before they enter the flared guide, and the action of the guide is to position the blanks substantially in line with the grinding faces of the wheels. Owing to the difference of speed and direction of movement of the carrier and the grinding wheels, the

slower moving carrier provides the requisite resistance to accomplish the grinding. Where both ends of the blanks are being simultaneously ground, it will be seen that one 5 wheel backs up the other, but where only one surface is to be ground, the other wheel may be replaced by a guide disk or by a stationary abutment, along which the blanks will slide. Where the head of a bolt is to be 10 ground to a uniform length, the carrier acts as the abutment, and the other wheel will simply be moved back out of the way. By changing the shape of the holes in the carrier 9 different shaped blanks can be ground, 15 the holes receiving the blanks lengthwise and the carrier being thinner than the finished length of the blanks so that the blanks can revolve in the carrier in the usual manner. The wheels can revolve in the same 20 direction, or oppositely at different speeds, as in my Patent 1,210,937, Jan. 2, 1917, in which case the slower moving wheel acts as a regulating wheel.

This invention can be made in the form of 25 an attachment which can readily be adapted to existing grinding machines and thereby increasing the capacity thereof and enabling large quantities of small articles to be ground to uniform lengths. Various modifications may be made in the structure herein 30 illustrated without departing from the scope of the appended claims.

What is claimed, is:

1. The combination with a grinding wheel, 35 of a rotating carrier provided with holes or pockets to receive the blanks to be ground, and a guide arranged adjacent said grinding wheel and having an outwardly flaring or rearwardly tapering entrance so that said 40 guide will position said blank relative to said grinding wheel.

2. The combination with a grinding wheel,

of a rotating carrier provided with holes or pockets to receive the blanks to be ground and having a geared periphery, a rotating 45 pinion meshing with the said geared periphery of said carrier, and means for positioning the blanks inserted in said carrier before they reach said grinding wheel.

3. A grinding machine attachment comprising a suitable base, a support or standard separate from said base but attached thereto, a bracket separate from said standard but rigidly secured thereto, a rotating carrier mounted in said bracket and having 50 holes or pockets to receive the articles to be ground, and means, also mounted on said bracket, for rotating said carrier.

4. A grinding machine attachment comprising a suitable base, a support or standard separate from said base but attached thereto, a bracket separate from said standard but rigidly secured thereto, a rotating carrier mounted in said bracket and having 55 holes or pockets to receive the articles to be ground, said carrier having a geared periphery, a shaft also mounted on said bracket and provided with a pulley, and a pinion on said shaft for rotating said carrier.

5. A grinding machine attachment comprising a suitable support or standard, a bracket attached to said support or standard, a rotating carrier mounted in said bracket and having holes or pockets to receive the blanks to be ground, means also 70 mounted in said bracket for rotating said carrier, and guiding means, also mounted in said bracket, for positioning the blanks inserted in said carrier before they reach the grinding wheel or wheels of the grinding 75 machine.

In testimony whereof I affix my signature.

LEWIS R. HEIM.
